(57) **CLAIM**

The ornamental design for a snorkeling mask, as shown and described.

DESCRIPTION

FIG. 1 is a front elevational view of a snorkeling mask showing my new design;

FIG. 2 is a rear elevational view thereof;

FIG. 3 is a left side view thereof;

FIG. 4 is a right side view thereof;

FIG. 5 is a top plan view thereof;

FIG. 6 is a bottom plan view thereof;

FIG. 7 is a top perspective view thereof; and,

FIG. 8 is bottom perspective view thereof.

The broken lines in the drawings illustrate portions of the snorkeling mask that form no part of the claimed design.
